UNITED STATES PATENT OFFICE

114,554

DESIGN FOR A COMBINED BICYCLE FRAME AND CONTAINER

John R. Morgan, Oak Park, Ill., assignor to Sears,
Roebuck and Co., Chicago, Ill., a corporation
of New York

Application November 18, 1938, Serial No. 81,202

Term of patent 7 years

To all whom it may concern:

Be it known that I, John R. Morgan, a citizen
of the Republic of Guatemala, residing at Oak
Park, in the county of Cook and State of Illinois,
have invented a new, original, and ornamental
Design for a Combined Bicycle Frame and Con-
tainer, of which the following is a specification,
reference being had to the accompanying draw-
ing, forming a part thereof.

Fig. 1 is a top plan view of a combined bicycle
frame and container embodying my new design.

Fig. 2 is a side elevational view of the same.

I claim:

The ornamental design for a combined bicycle
frame and container, as shown.

JOHN R. MORGAN.
